COASTER RACK

George J. Strauss, 6606 10th Ave., Los Angeles 43, Calif.

Filed Apr. 19, 1963, Ser. No. 74,527

Term of patent 3½ years

(Cl. D44—29)

FIG. 1 is a perspective view of a coaster rack showing my new design;

FIG. 2 is a side elevational view;

FIG. 3 is a top plan view;

FIG. 4 is a front elevational view;

FIG. 5 is a rear elevational view; and

FIG. 6 is a sectional view taken on line 6—6 of FIG. 2.

The side opposite that shown in FIGS. 1 and 2 is a mirror image thereof.

The coasters shown in broken lines in FIGS. 1 and 4 are for illustrative purposes only.

I claim:

The ornamental design for a coaster rack, substantially as shown and described.
